RABBLE ARM

Application filed October 8, 1928. Serial No. 311,110.

This invention relates to rabble arms or stirring devices for use in furnaces in which ores, for instance, sulphide ores, are subjected to the process of roasting as a step preliminary to the process of reduction.

Practically all sulphide ores have to be subjected to some sort of roasting or sintering operation before they are finally reduced to their metallic constituents, and this operation is carried on in some form of furnace which generally comprises a heating chamber with a rotating stirring device adapted to agitate the ore during its treatment, and commonly termed a "rabble arm." Such a rabble arm preferably consists of a central upstanding column carrying a member extending laterally therefrom at a level which causes said member (or projections carried thereby) to enter and stir up the mass of ore being roasted; the laterally extending member being in some cases separately produced and detachably connected with the column to facilitate replacement in cases of failure, and in other cases made integral with the column.

Heretofore, in order to withstand the heat incident to the roasting operation, the column of the rabble arm has had a construction which permits a cooling medium to circulate through it, and it has been found desirable in some instances to extend this cooling principle to the laterally extending member as well.

But artificial cooling of such stirring devices lends complication to the equipment and is uneconomical in operation, not only because of the expense of keeping up the cooling influence but because of the heat conveyed away by the cooling medium.

Attempts have been made to construct rabble arms without artificial cooling equipment, dependence being placed upon the selection of a metal for the rabble arms capable of resisting very high temperatures, for instance, a high-chromium steel alloy. But it was found that, owing to the low strength of the heat resistance alloy, at high temperatures and the high stresses set up by the heavy loads, both static and of torque, non-cooling stirring devices made of such alloys

failed in use. This failure is due partly to the employment of structural designs inadequate to meet the stresses encountered by the rabble arm in service at the high temperatures incident to the sintering operation, and partly because of the excessive heat conducted by the rabble arm beyond the furnace wall through which it must extend in receiving its support and drive from exterior mechanism.

The present invention avoids the difficulties heretofore encountered, and provides a rabble arm of high temperature alloy adapted for overhead suspension, capable of withstanding the stresses encountered in use, notwithstanding the high temperature of the furnace, and one which avoids excessive conduction of heat through the top wall of the furnace.

To these ends, the invention proceeds upon the principle of constructing the rabble arm with its depending shaft member through which it is suspended and driven, and its laterally extending member which constitutes the sweep, of one single piece, preferably a casting of high temperature alloy;

these members constituting hollow structures of relatively large internal dimensions with comparatively thin walls; the upper end of the shaft being formed with a bottleneck shank which extends through the furnace arch for connection with the external supporting and driving mechanism; and the lateral member merging with the shaft member

through means of a curved elbow construction and tapering downwardly and outwardly from the dimensions of the shaft member, thereby producing a construction which, notwithstanding the reduced inherent strength of the metal at high temperatures,

is peculiarly adapted to meet the stresses encountered by the rabble arm in use, which involve both torsional and bending moments in each member as well as a complication of these moments of stress at the elbow through which the two members merge.

In the accompanying drawing, which illustrates the preferred embodiment of the invention by way of illustration—

Figure 1 is a side elevation of the rabble

arm with the portion of the furnace arch with which it is concerned, shown in section.

Figure 2 is an elevation of the rabble arm as viewed from the right in Figure 1; and

5 Figures 3 and 4 are, respectively, a bottom and a top plan view of the rabble arm.

10 1 represents the vertical portion or column of the rabble arm, provided at the top with a coupling flange 2, and 3 represents the laterally extending member of the arm. These members are formed in one piece and are of hollow construction with large interior dimensions so that their walls, as indicated in

15 dotted lines, are thin compared with their overall transverse dimensions. The member 3 merges with the member 1 through an elbow construction 5, 6, which is curved on the internal angle, through which curvature the structure merges from the hollow cylindrical

20 depending shaft 1 to the downwardly and outwardly tapering sweep member 3. As shown in Figure 2, the base 7 of the laterally extending member or sweep 3 is of materially less transverse dimension than

25 the shaft 1 or even the upper inner portion of the sweep, and is provided with marginal flanges 8 having perforations 8a through which the rabble arm is adapted to receive the so-called blades or other elements commonly used with rabble arms of this kind for stirring up the material. This construction of sweep member as will be appreciated by comparing Figure 2 with Figure 1, affords great strength and resistance to bending

35 and torsional stresses encountered in use, as well as ample strength vertically to resist bending stresses, particularly at the elbow 5, 6. Moreover, the construction, embodying as it does the relatively large hollow shaft

40 1 merging with the hollow downwardly and outwardly tapered sweep 3 through means of the curved elbow, results in a very strong and efficient structure as a whole under stresses necessarily encountered in the rotation of a vertical shaft with a relatively long sweep

45 extending laterally therefrom, and carrying stirring elements that drag through the mineral mass commonly treated with the use of rabble arms. Coupling flange 2 is of usual

50 dimensions for attaching to standardizing driving mechanism for rabble arms in furnaces of the kind for which the present invention is intended, and beneath this coupling flange and the portion of the column 1 which passes through the arch A of the furnace, is a reduced neck portion 4, which is of quite sufficient stress-resisting capacity because of relatively lower temperatures encountered there, and which thereby affords the desired conditions of reduced capacity for transmitting heat (convectional transmission of heat being largely choked by the bottle-neck construction, and heat conduction being reduced by the decreased section of the

metal); also, small subtraction of arch area, and standardized coupling facilities.

The main body of the column or shaft and the laterally extending member have walls of such thickness combined with such relatively large sectional diameter as to make a structure that is very strong and rigid, even when made of high chromium iron alloy and at roasting furnace temperatures; the expense of providing and operating cooling influences is avoided, and heat losses incident to artificial cooling are saved.

I claim:

1. A non-cooled rabble arm for furnaces, comprising an upstanding column or shaft adapted to extend through a confine of a furnace and having a laterally extending member through which it is adapted to stir the contents of the furnace; said rabble arm being constructed with relatively large hollow transverse dimensions at its portions which encounter the higher temperatures incident to its use, and with relatively small transverse dimensions providing choking of heat conduction and convection and reduced furnace surface interruption at the portion which passes through the furnace confine; said shaft having upon the upper end of said reduced portion, means for establishing suspending and driving connection with external mechanism, and the laterally extending member being united with the column or shaft through a curved elbow and tapering downwardly and outwardly therefrom.

2. A non-cooled, overhead suspension rabble arm for furnaces, comprising a depending shaft member constructed with a vertical hollow body portion of relatively large diameter, an upper end portion of relatively smaller diameter by which the shaft member intersects the top confine of the furnace and through which the rabble arm is suspended and driven when in service, and a constricted free lower end; and a laterally projecting hollow sweep member having a relatively large downwardly inclined and laterally tapered upper portion merging at its inner end through curved continuing surfaces, with major transverse dimensions of the body portion, and having a relatively narrow substantially horizontal lower portion formed by parallel vertical sides that merge at their inner ends with the constricted free end of the shaft member; the bottom confine of said sweep comprising a substantially flat wall uniting the said sides and having flanges extending beyond the same.

Signed at Chicago, Illinois, this 19th day of September, 1928.

FRANK A. FAHRENWALD.
